CLARENCE RINGWALD, OF CHICAGO, ILLINOIS, ASSIGNOR OF ONE-HALF TO JOHN A. DIENNER, OF EVANSTON, ILLINOIS.

DRIVE FOR ENGINE STARTERS.

REISSUED

Application filed October 24, 1924. Serial No. 745,555.

My invention relates to drives for engine starters. I am aware that heretofore it has been the practice in starting internal combustion engines to employ a threaded sleeve mounted upon the motor shaft and connected to said motor shaft by a spring-connection. An internally threaded drive pinion forms a nut for said threaded sleeve and it is moved axially into mesh with the ring gear on the fly wheel of the engine by rotation of the motor shaft and its threaded sleeve, and after the nut or pinion is meshed with said ring gear, it is rotated to turn the fly wheel and thus crank the engine.

In such devices, the parts must fit loosely and move easily, because the pinion nut is held by inertia while it moves axially into mesh with the ring gear. Since the sleeve is interposed between the pinion and the shaft, there is excessive play and lost motion with consequent friction in the gear teeth and inaccuracy in fit of the parts. The interposition of the sleeve also demands a pinion of larger diameter with consequently less leverage.

According to my invention, I make the parts fewer in number by having the pinion provided with an axially extending sleeve which sleeve and pinion are unitary and fit upon the motor shaft. An external nut connected through a spring connection with the motor shaft then serves to thread the pinion and its sleeve into mesh with the ring gear on the fly wheel and thus secure meshing between the driving pinion and the ring gear.

By the employment of my invention, it is possible to use a pinion of smaller diameter with a consequent increase in starter ratio. The use of my invention gives greater inertia to the pinion without the addition of extra material for that purpose. The pinion, furthermore, is now mounted upon the ground motor shaft with a fine fit, thereby securing accurate centering and better support, not only from the motor shaft, but also from the bearings of the motor. Also there is less pounding and tilting of the pinion.

Furthermore, the construction permits the pinion to be driven closer to the bearing of the starter motor, so that longer life and better wearing qualities are assured. Above all, the construction is cheaper than any

heretofore proposed with which I am familiar.

In order to acquaint those skilled in the art with the manner of constructing and operating my invention, I shall now describe a specific embodiment of the same in connection with the accompanying drawing, in which:

Figure 1 is a side elevational view of a device embodying my invention;

Fig. 2 is a vertical longitudinal sectional view through the same;

Fig. 3 is a transverse section taken on the line 3—3 of Fig. 2; and

Fig. 4 is a similar transverse section taken on the line 4—4 of Fig. 2.

The bearing 1 of the driving motor supports the motor shaft 2, this motor shaft having a shoulder 3 and a reduced portion 4 extending therefrom, this reduced portion being carefully ground to fit the interior of the pinion and sleeve member 5 which fits upon said shaft 4. The pinion and sleeve member 5 is a unitary member comprising a pinion 6 and a threaded portion 7 extending to the rear of the same. Upon the rear end of the threaded sleeve 7 I provide an unbalanced stop nut 8 which is securely fastened upon the rear end of the threaded part 7 to provide a stop in conjunction with the driving nut 9 when the two parts are engaged. This stop nut 8 is eccentric and is preferably threaded upon the end of the threaded sleeve 7 by screw threads of fine pitch inclined in a direction such as to produce tightening of the nut 8 thereupon when it engages the nut 9. The threaded sleeve 7 has screw threads of coarse pitch and preferably of multiple thread.

The nut 9 is connected to the end of a suitable spring 10, the end of the spring being formed into a loop or eye at 11 and the machine screw 12 passing radially through said eye 11 and into the nut 9 and being held against rotation by a suitable bendable lock washer 13.

At the outer end of the motor shaft 4, I provide a collar 14, to which the outer end of the spring 10 is connected in a similar manner to its connection through the nut 9. The outer end of the spring 10 has an eye 15 through which passes a bolt 16, this bolt being passed into the body of the collar 14

and engaging the end of the shaft 4. The shaft 4 is keyed to said collar 14 in addition to the engagement of the bolt 16 for rigidly connecting said collar 14 and the end of 5 the shaft 4.

A pair of sheet metal sleeve members 17 and 18 are passed under the ends of the spring 10 on the collar 14 and the nut 9, respectively, these sheet metal sleeves serving 10 to exclude foreign matter from the threads of the sleeve 7, and serving also as a support for the convolutions of the helical spring 10, and as a container for lubricant.

The pinion 6 and shaft 4 are mounted 15 closely adjacent the ring gear 21 on the fly wheel 22 of the motor, the parts being so designed as to permit the pinion 6 to run axially up to the shoulder 3 or closely adjacent thereto, when the stop nut 8 engages the 20 end of the driving nut 9.

The operation of the device is as follows: The shaft 4, being set closely adjacent the ring gear 21 and in proper endwise adjustment, rotation of the motor shaft 2 in a 25 counter clockwise direction as viewed from the right of Figs. 1 and 2 results in a movement of the connected parts, namely, the collar 14, bolt 16, spring 10, bolt 12, and driving nut 9. The inertia of the pinion and 30 sleeve member 5, together with the eccentric nut 8, tends to hold these parts against rotation while the nut 9 is rotated to advance the pinion 6 axially, until it strikes the teeth of the ring gear 21 and meshes 35 with the same, whereupon engagement of the stop collar 8 with the end of the driving nut 9, results in rotation of the pinion 6 and consequent driving of the ring gear 21 to 40 crank the engine. Upon starting of the engine in the same direction at a speed greater than the speed of the nut, the member 5 comprising the pinion 6 and the threaded sleeve 7, will be carried back axially to the left, as indicated in Figs. 1 and 2. It will be obvious that, if desired, a collar may be provided at the left end of the pinion 6 as 45 shown in Figs. 1 and 2, or that if desired the pinion 6 may be run up against the shoulder 3 on the shaft 2. On the return motion the pinion stops by engaging the outer face of collar 9.

From the foregoing, it will be seen that I have provided a construction which permits 55 of a pinion of a minimum number of teeth and of a minimum diameter, in order to secure a maximum starting ratio. At the same time, the rearwardly extending threaded sleeve 7 gives the pinion 6 greater inertia without increasing the diameter 60 of the same and thus makes for certainty of operation. The pinion 6 is held accurately and with much greater bearing on

the ground shaft section 4 than has been possible in devices of the prior art. It will be noted that the pinion can now be brought 65 up to the motor bearings, since no collar is required at the inner end of the pinion as in devices of the prior art, and better support is thereby gained. In addition to the above advantages, the construction is less expensive 70 and involves a less number of parts.

I claim:

1. In combination, a sleeve member bearing a coarse external thread and having a pinion on one end, a threaded collar on said 75 threaded part of the sleeve member, an attaching collar, a helical drive spring concentric with said sleeve between said two collars and a stop on the threaded end of the sleeve for engaging the threaded collar to 80 stop the forward movement of the member.

2. In combination, a driving shaft, an externally threaded sleeve on said shaft having an integral pinion at one end, an internally threaded collar embracing the threads on 85 said sleeve, a stop collar on the end of the sleeve opposite said pinion, a collar non-rotatably secured to said driving shaft, and a helical spring connecting said last named collar and said internally threaded collar 90 and extending over the end of said sleeve and its attached stop collar.

3. In combination, a rotatable motor shaft, a one-piece sleeve and pinion member mounted directly on said shaft, a threaded nut embracing the sleeve, a collar on the end of the motor shaft and a coil spring between said 95 collar and said nut and telescoping over said sleeve.

4. In combination, a one-piece sleeve and 100 pinion member adapted to be mounted on a driving shaft, a threaded nut on said sleeve, said sleeve having a threaded portion with a shoulder at the rear end of the threaded portion, an attaching collar mounted on and 105 secured to the motor shaft, and a helical connecting spring between the collar and the nut.

5. In combination, a motor shaft adapted 110 to be closely positioned adjacent a ring gear for an internal combustion engine, a threaded sleeve and pinion member mounted directly on said shaft, said pinion forming a shoulder at one end of the threaded sleeve 115 and a stop collar mounted at the other end of the threaded sleeve and forming a shoulder, a threaded nut between said shoulders on said threaded sleeve, a collar secured on the outer end of the motor shaft and a coil spring connecting said collar with said 120 threaded nut and embracing the sleeve.

In witness whereof, I hereunto subscribe my name this 21 day of October, 1924.

CLARENCE RINGWALD.
